UNITED STATES PATENT OFFICE.

JULIUS H. SCHLAFLY, OF CANTON, OHIO, ASSIGNOR TO THE BERGER MANUFACTURING COMPANY, OF SAME PLACE.

DESIGN FOR A PUMP-STOCK.

SPECIFICATION forming part of Design No. 33,334, dated October 9, 1900.

Application filed August 11, 1900. Serial No. 26,654. Term of patent 7 years.

To all whom it may concern:

Be it known that I, JULIUS H. SCHLAFLY, a citizen of the United States, residing at Canton, in the county of Stark and State of Ohio, 5 have invented and produced a certain new and original Design for a Pump-Stock, of which the following is a specification.

The invention relates to a new and original design for pump-stocks; and it consists of the design shown in the accompanying drawings, in which I have illustrated the invention in perspective.

The leading feature of the design consists of a cylindrical body 1, provided with longitudinal flutes or corrugations 2 and with a

smooth cylindrical portion 3 at its lower end, a conical cap 4 at its upper end, and an intermediately-disposed tapering band 5, having corrugations 6, a spout 7, a corrugated band 8, and parallel webs 9 and 10. 20

What I claim is—

The design for a pump-stock as herein shown and described.

In testimony whereof I have hereunto set my hand in the presence of two subscribing 25 witnesses.

JULIUS H. SCHLAFLY.
